Attorneys

UNITED STATES PATENT OFFICE.

HOWARD L. WEED, OF DETROIT, MICHIGAN.

ROTARY ENGINE.

1,328,410.

Specification of Letters Patent.

Patented Jan. 20, 1920.

Original application filed September 7, 1915, Serial No. 49,153. Divided and this application filed July 29, 1918. Serial No. 247,176.

To all whom it may concern:

Be it known that I, HOWARD L. WEED, a citizen of the United States, and residing at Detroit, in the county of Wayne and State of Michigan, have invented a new and Improved Rotary Engine, of which the following is a specification.

The present invention has reference to an internal combustion engine of the rotary alternating piston type, more particularly to means for sealing the joints between the rotors and the casings and between the two rotors.

As to the first named feature of the invention, it consists in a floating ring interposed between the rotors and adapted to both close the joint between the rotors and to reduce friction.

The second feature of the invention consists in a ring construction comprising an expandible ring adapted to engage with a flaring surface to thereby wedge itself over toward the corresponding rotor.

It further consists in a ring of this nature mounted in a ring carrier and arranged to wedge the latter over against the rotor. Again, it consists in a ring carrier having an annular pocket therein adapted to collect such gas as may leak through between the ring and the flaring surface.

The invention further consists in the details of construction shown, described and claimed.

This application is a division of my application for patent Serial Number 49,153, filed Sept. 7, 1915.

In the drawing, Figure 1 is a longitudinal section of enough of an engine to show one embodiment of the invention. Fig. 2 is an enlarged fragmentary section showing the sealing means more clearly. Fig. 3 is a fragmentary perspective view showing a preferred joint between the ends of one of the sealing rings.

In the embodiment of the invention shown, the fixed casing includes the two intermediate sections 1 and the two end sections 2, each of the former including half of the ring-shaped cylinder 3 and each of the latter having bearings 4 for the main engine shaft 5. Loosely mounted on the engine shaft in opposed relation to one another are the sleeves 8 and 9 to which the disks 10 and 11 of the rotors are secured. Between the disks and loose upon the shaft

is a packing and friction reducing disk 15 having an outer substantially flat portion or ring 16 against which the flat annular surfaces 18 on the rotor disks directly engage to form tight joints.

These rotors each include a pair of pistons 19, but one of each pair being shown, and both travel in a forward direction each one alternately traveling forwardly faster than the other, thus securing the different phases of the cycle in a well known manner. The piston construction, as well as one form of mechanism whereby the relative movement of the rotors may be caused to rotate the shaft 5 is shown in my above identified application, these parts being omitted in the present case inasmuch as the invention claimed herein is concerned with other matters. It will be understood that the disk 15 rotates about the shaft in accordance with the relative movement of the rotors.

In order to seal the joints between the rotors and the casing sections, the latter are extended radially inwardly at 78 and terminate in the cylindrical flanges 79, these members forming two sides of annular pockets or grooves. The outer surfaces of said grooves are cylindrical for substantially half their depths, as indicated at 80, and have their other halves flaring to the rotor disks at 81. Seated within the pockets are ring carriers, each of which includes the base 82, the inner flange 83, the outer flange 84 and the intermediate flange 85, that are parallel to each other and project at right angles to the base. The space between the outer and intermediate flanges receives the resilient packing ring 88, one end of which is grooved at 89, the other end having a tongue 90 fitting therein. Similarly, a second packing ring 91, differing from the ring 88 merely in that its outer surface is inclined or flared to conform to the surface 81, is interposed between the flanges 83 and 85. It will be understood that the resiliency of the springs is such as to normally hold them in rather close engagement with the surface 80-81. The outer edge of the flange 85 is preferably grooved circumferentially at 92.

A certain amount of leakage may occur between the ring 91 and the surface 81, and this gas may reach the groove 92. One component of its pressure thrusts the carrier 82-83-84-85 against the corresponding

rotor disk sufficiently to maintain a proper seal between the flat surfaces of contact. It will be noted that a similar action is caused by the resiliency and inclined surfaces of the packing rings. Such gas as escapes into the groove 92 merely pushes the ring 88 over against the flange 84 without affecting the engagement of the ring 88 with the cylindrical surface 80. The fit of the parts is loose enough to allow the ring carrier and rings to be carried around in the pockets, a feature of considerable importance, since the difference in temperatures between the zone of ignition and the zone of intake is sufficient to set up local stresses that otherwise might cause binding and consequent wear between the flange 83 and the rotor disk.

The details of construction may be changed considerably without departing from the spirit of my invention, and I do not, therefore, wish to be limited except as indicated by the subjoined claims.

I claim:

1. A rotary engine comprising a casing that includes a cylinder, an engine shaft mounted in the casing, rotors comprising disks concentric with and loose upon the engine shaft, pistons traveling in the cylinder, said pistons being rigid with the corresponding rotor-disks, a disk loose upon the engine shaft under all conditions and interposed between the rotor-disks, said rotor-disks being arranged to closely engage the last mentioned disk to insure a tight seal for the cylinder, and means for transmitting motion from the rotors to the engine shaft.

2. A rotary engine comprising a casing that includes a cylinder, an engine shaft mounted in the casing, rotors comprising disks concentric with and loose upon the engine shaft, said disks including flat annular rings along their outer margins, pistons traveling in the cylinder, said pistons being rigid with the corresponding rotor-disks, a disk always loose upon the engine shaft and interposed between the rotor-disks, said last mentioned disk including flat annular rings along its outer margin with which the annular rings on the rotor-disks respectively engage, whereby a close seal between the parts is secured, and means for transmitting motion from the rotors to the engine shaft.

3. A rotary engine comprising a casing in which a cylinder is formed, an engine shaft mounted in the casing, a rotor comprising a disk co-axial with the engine shaft, said rotor also including a piston that travels in the cylinder, said casing having an annular pocket opening toward the rotor-disk along the outer edge of the latter, the pocket tapering inwardly from the opening, an annular ring carrier floating in the pocket, said ring carrier including a

base and a pair of spaced flanges projecting therefrom, an expansible sealing ring carried by the ring carrier, said ring bearing against and conforming to the tapering surface of the pocket, whereby the ring carrier is forced laterally into frictional engagement with the rotor-disk.

4. A rotary engine comprising a casing in which a cylinder is formed, an engine shaft mounted in the casing, a rotor comprising a disk co-axial with the engine shaft, said rotor also including a piston that travels in the cylinder, said casing having an annular pocket opening toward the rotor-disk along the outer edge of the latter, the pocket tapering inwardly from the opening, an annular ring carrier floating in the pocket, said ring carrier having a circumferential groove therein, an expansible sealing ring carried by the ring carrier, said ring bearing against and conforming to the tapering surface of the pocket, whereby the ring carrier is forced laterally into frictional engagement with the rotor-disk.

5. A rotary engine comprising a casing in which a cylinder is formed, an engine shaft mounted in the casing, a rotor comprising a disk co-axial with the engine shaft, said rotor also including a piston that travels in the cylinder, said casing having an annular pocket opening toward the rotor-disk along the outer edge of the latter, the pocket tapering inwardly from the opening for a portion of its depth, the remainder of the pocket having its walls perpendicular to the rotor-disk, an annular ring carrier floating in the pocket, said ring carrier having spaced circumferential grooves therein, a sealing ring carried in one of the grooves and having its surface conforming to the wall of the tapering portion of the pocket, whereby the ring carrier is forced laterally into frictional engagement with the rotor-disk and leakage is avoided.

6. A rotary engine comprising a casing in which a cylinder is formed, an engine shaft mounted in the casing, a rotor comprising a disk co-axial with the engine shaft, said rotor also including a piston that travels in the cylinder, said casing having an annular pocket opening toward the rotor-disk along the outer edge of the latter, the pocket tapering inwardly from the opening for a portion of its depth, the remainder of the pocket having its walls perpendicular to the rotor-disk, an annular ring carrier floating in the pocket, said ring carrier including a base and three spaced parallel flanges projecting therefrom whereby two circumferential grooves are formed, one of the flanges bearing on the rotor-disk, a sealing ring carried in the groove adjacent the last mentioned flange and conforming to the wall of the tapering portion

- of the pocket, a second sealing ring carried in the other groove and conforming to the wall of the remaining portion of the pocket, there being a circumferential groove in the 5 wall of the second intermediate flange nearest the first groove for the reception of gases that leak past the first sealing ring.
7. A casing, a rotor-disk revoluble therein, said casing having an annular pocket 10 opening toward the rotor-disk along the outer edge of the latter, said pocket tapering inwardly from the opening for a portion of its depth, the remainder of the pocket having its walls perpendicular to the rotor-disk, and a pair of sealing rings located in 15 the pocket, one conforming to the tapering portion of the pocket and the other to the remaining portion.
8. A casing, a rotor-disk revoluble therein, said casing having an annular pocket 20 opening toward the rotor-disk and having a portion tapering away from said rotor-disk, a ring carrier therein bearing on the rotor-disk, and a sealing ring co-acting with the tapering portion of the pocket and with the 25 carrier to crowd the latter over against the rotor-disk.
9. An engine comprising a casing, a rotor-disk revoluble therein, said casing having an annular pocket opening toward the 30 rotor-disk, a ring carrier in the pocket and bearing on the rotor-disk, and a sealing ring supported by the carrier and pressing on the wall of the pocket.

HOWARD L. WEED.
